6. COMPOSITIONS,
COATING OR PLASTIC.

UNITED STATES PATENT OFFICE.

FRANK CORDERY, OF MONROE, MICHIGAN.

BRICK COMPOSITION.

1,218,239.

Specification of Letters Patent.

Patented Mar. 6, 1917.

Application filed June 20, 1916. Serial No. 104,814.

To all whom it may concern:

Be it known that I, FRANK CORDERY, a subject of the King of Great Britain, and a resident of Monroe, in the county of Monroe and State of Michigan, have invented a certain new and useful Brick Composition; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to brick compositions. It particularly relates to the making of bricks which may be used for fixing blocks for securing strips, molding, panels, mop boards or the like to brick, cement or stone walls. Nails or screws may be driven or threaded into the brick-like body embodying my invention with the ease that they may be driven or screwed into wood, and moreover, they will be securely retained. 20 The bricks may be placed in a wall such as a brick partition in a building, for the purpose of securing trim thereto. The bricks may be laid upon cement or other fire resisting floors, or embedded in such floors, and the wood flooring may be nailed thereto. The object of the invention particularly is to provide a perfect fire-resisting non-shrinkable substitute for fixing blocks of wood commonly used for securing trim and 25 flooring, and which will form a perfect bond with masonry, brick-work or concrete, and will not be subject to shrinkage, dry rot, or decay, and which will receive and retain nails, screws, bolts or other attachments, and 30 which will retain such fastening means as well as wooden blocks and strips commonly used in building construction.

For the purpose of illustrating the utility of the invention, the bricks are shown in 45 the accompanying drawing, wherein Figure 1 shows a section of a partition wall in which the bricks embodying my invention are contained for the purpose of securing the trim, such as a panel board or mop board. 50 The figures are broken views of the same wall. Fig. 1 shows a layer of bricks containing my invention and a border strip for the panel of the wall secured thereto, and

Fig. 2 illustrates a mop board which is secured by the bricks embodying my invention. 55

1 in the figures is the wall. 2 are the bricks formed of the composition containing my invention, and 3 are ordinary tiled bricks or partition bricks of which the wall is formed. Any suitable arrangement may 60 be made with reference to the bricks embodying my invention. In order to secure the mop board a tier of bricks may be laid, and in order to secure the border on the panel the bricks containing my invention 65 may be laid on the tile bricks at the proper height. The mop board may then be secured in position by driving a nail through the mop board 4 and the plaster 5, and into the bricks 2, whereupon the mop board will 70 be securely retained. If desired, screws may be used, as shown, in fastening the border 6 of the panel. The screws 7 are passed through the border strip 6 and 75 threaded into the bricks 2.

The composition of the bricks, which have large compressional strength and at the same time are fire-resisting, and will not crumble, and yet which will receive and retain nails, screws, etc., and from which the nails and screws and bolts may be withdrawn without breaking the brick, is formed of a mixture of cinders, clinkers and cement, to which is added a certain amount of mortar coloring, such as oxid of iron, which 80 may be in the form of colored earth or earth containing considerable oxid of iron. The mixture is rendered plastic by adding water. More specifically the composition is 85 formed by using three parts of ground or finely broken engine cinders and three parts of ground or broken clinkers, one part of coloring earth, one part of earth containing oxid of iron and one part of cement. This is mixed together with the requisite 90 amount of acidulated water to render the whole plastic, necessary for molding purposes, such as for the making of concrete 95 bricks. The cinders may be of any form. The preferred cinders are like those which issue forth from the smoke pipe of a railroad engine or furnace when under forced draft. Also the clinkers may be of any form, the preferred form being like those from the fire box of an engine. It is found 100 preferable to acidulate the water, which 105
